(57) **CLAIM**

The ornamental design for a measuring tool of body size, as shown and described.

DESCRIPTION

FIG. 1 is a top front perspective view of a measurement tool of body size of my present invention.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is an bottom plan view thereof.

Portions not illustrated form no part of the claimed design. No claim is made to the inner portions of the inventions or disclaimed portions demarcated by dash-dash disclaim lines. The surface shading lines illustrate contour only and form no part of the present design. The dash-dash disclaim lines indicate portions which form no part of the claimed design. The present invention is a measuring tool of body size in the form of a surface indicia arrangement on a device worn by a user.
